UNITED STATES PATENT OFFICE.

GEORGE M. PELTON, OF MILWAUKEE, WISCONSIN, ASSIGNEE TO THE FILER & STOWELL COMPANY, OF MILWAUKEE, WISCONSIN, A CORPORATION OF WISCONSIN.

WOOD-CHIPPING MACHINE.

1,114,031.

Specification of Letters Patent.

Patented Oct. 20, 1914.

Application filed January 3, 1911. Serial No. 600,401.

To all whom it may concern:

Be it known that I, GEORGE M. PELTON, a citizen of the United States, residing at Milwaukee, in the county of Milwaukee and State of Wisconsin, have invented certain new and useful Improvements in Wood-Chipping Machines, of which the following is a specification, reference being had to the accompanying drawing, forming a part thereof.

This invention relates to machines known as saw mill hogs for cutting refuse lumber into chips for fuel. Its main object is to improve the construction and operation of machines of this kind, and it consists in the construction, arrangement and combination of parts as hereinafter particularly described and pointed out in the claims.

In the accompanying drawing like characters designate the same parts in the several figures.

Figure 1 is a side elevation of a machine embodying the invention; Fig. 2 is a plan view of the same; Fig. 3 is a vertical longitudinal section thereof on the line 3 3, Fig. 4; Fig. 4 is a transverse vertical section on the line 4 4, Fig. 3; Fig. 5 is a longitudinal section on the line 5 5, Fig. 3, of a portion of the upper part of the case and of the main knives attached thereto; Fig. 6 is a sectional detail on the line 6 6, Fig. 3, showing a portion of the rotary cutter head and one of its knives; and Fig. 7 is a section on the line 7 7, Fig. 3, showing a guard at one side of the feed opening and adjacent portions of the case and cutter head.

The case of the machine is composed of a boxlike base *a*, of substantially quadrangular form, outwardly flanged and open at the top and bottom and of two approximately quarter cylindrical sections *b* and *c*, outwardly flanged around their edges and fitted together and to the base on which they are mounted. The base is formed or provided on opposite sides with boxes *d*, in which the shaft *e* of a rotary cutter head *f* is mounted and held against endwise play by collars *g*, shown in Fig. 4. The cutter head is composed of two truncated conical sections bolted together and keyed on the shaft *e*, as shown in Figs. 3 and 4. The inwardly converging faces or walls of the cutter head are formed with radially disposed staggered

openings *h*, in which knives *i* are fitted and adjustably fastened by bolts *j*, as shown in Figs. 4 and 6.

The section *b* of the case, which is permanently bolted to the base *a*, is formed in the upper part thereof with a feed opening surrounded by an upwardly or outwardly projecting flange *k* for the connection therewith of a feed spout (not shown) and side guards *l*. Below this feed opening the peripheral wall of section *b* is made of V-shape in cross section, as shown in Figs. 2 and 3, to conform with the conical faces of the cutter head and close the space between them and the case, the upper wall *m* of this inwardly projecting part of the section forming a continuation of the flange *k* on the lower side of the feed opening, and serving to prevent pieces of wood as they are fed to the machine from dropping into the lower part of the case before they are reduced to chips by the rotary cutter head.

The guards *l*, as shown in Figs. 3 and 7, have inner curved and beveled edges which extend inwardly into close proximity with the conical faces of the cutter head *f* adjacent to and within their outer margins, and prevent splinters or pieces of wood from escaping between the sides of the cutter head and the sides of the case without being subjected to the action of the knives.

Section *c*, which is similar in general shape to the feed section *b* of the case, is formed in the upper part thereof with inwardly converging knife seats or supports *n*, approximately tangent to the conical faces of the cutter head *f*, as shown in Figs. 2, 3, 4 and 5. These seats or supports terminate along their outer edges with inwardly offset shoulders or walls *o*, in which adjusting screws *p* are threaded. To the inner faces of the seats or supports *n* are adjustably fastened knives *q*, by bolts *r* passing through countersunk holes in the knives and transversely slotted openings in the seats or supports *n* and provided on their outer exposed ends with nuts. The adjusting screws *p* and the nuts on the clamping bolts *r* are thus exposed on the outer side of the case and are easily accessible for adjusting and fastening the knives in place. The lower inwardly extended portion *s* of section *c* is faced to form a seat for an

auxiliary knife *t*, which is shaped to correspond with the converging faces of the cutter head *f* and is adjustably fastened to said seat by bolts *u* passing upwardly through 5 countersunk holes in said knife and slotted openings in the seat, and provided at their upper exposed ends with nuts, as shown in Fig. 3. The converging cutting edges of the knife *t* are thus disposed radially with respect to 10 the radial cutter head, or slightly above and parallel with its horizontal diameter, while the converging cutting edges of the knives *g* are set obliquely to the vertical diameter of the cutter head so as to produce a shearing cut with the knives *i*. The knife *t* serves 15 to reduce to chips any splinters or fragments of wood which may pass the knives *g*.

Section *c* is detachably fastened to the base *a* and section *b* by eye-bolts *v* pivoted 20 between lugs or ears cast on the base *a* and section *b*, and provided with nuts which are adapted to be swung into and out of place for engagement with forked or cleft lugs *w* cast on section *c*. Section *c* is connected at 25 the sides with the base *a* by links *x*, and at the end by a stop rod *y*, which is pivoted to the end of the base and passes loosely through a lug *z* on the end of section *c*. The stop rod is provided on its upper end projecting normally above the lug *z*, with a collar or nuts 2, and section *c* is provided on 30 the sides with lugs 3, which by engagement with the links *x* coöperate with the stop rod *y* and lug *z* to hold section *c* when removed 35 from the case, in convenient position as indicated by dotted lines on Fig. 1, for removing, replacing and adjusting the knives *g* and *t* and for gaining access to the knives *i* of the cutter head *f*, which are adjusted by gage to 40 run close to the cutting edges of the knives *g* and *t*. The shaft *e* of the cutter head is provided at one end outside of the case with a pulley or other means (not shown) for driving it.

45 In the operation of the machine, the cutter head *f* being rotated in the direction indicated by the arrow on Fig. 3, waste lumber is conducted through the feed spout into the upper part of the machine between the converging faces of the cutter head and between 50 the inclined wall *m* on the lower side of the feed opening and the opposite wall, connecting the seats *n* on the upper side of said opening. The knives *i* of the cutter head 55 carrying the pieces of wood forward against the stationary knives *g*, coöperate therewith to successively shear chips from the exposed sides of the pieces until they are completely cut into pieces, the chips passing outwardly 60 through the openings *h* in the cutter head and falling into the base, from which they are discharged through an opening or openings in the floor. Any splinters or fragments which may escape past the knives *g* 65 are caught by the auxiliary knife *t* and re-

duced to chips by the action of the knives *i* as they pass the converging cutting edges of the knife *t*.

The links *x* being connected at their lower ends with the base near the bottom and one end thereof and at their upper ends with section *c* back or outside of its center of gravity, make it easy to move said section, which with its attachments is quite heavy, out of and into place for the purpose of removing, sharpening and replacing or adjusting or renewing the knives *i*, *g* and *t*. In removing and replacing said section it is prevented from tipping inward beyond a certain limit by the engagement of the lug *z* with the nuts or shoulder 2 on the pivoted stop rod *y*, as indicated by dotted lines, Fig. 1.

I claim:

1. In a wood chipping machine the combination of a rotary cutter head having inwardly converging conical faces and provided with knives, a case in which said cutter head is mounted having a section formed with inwardly converging knife seats in planes approximately tangent to the conical faces of the cutter head, stationary knives removably attached to said converging seats and adapted to coöperate with the knives of the rotary cutter head, and a V-shaped knife removably attached to the case in a plane approximately radial to the cutter head and adapted to coöperate with the knives of the cutter head to reduce to chips fragments of wood escaping the other stationary knives.

2. In a wood chipping machine the combination of a case comprising a base and a knife supporting section mounted thereon and having inwardly converging knife seats terminating along their outer sides with laterally offset walls and formed with transversely elongated bolt holes, knives fitted to said seats, bolts passing through said knives and the holes in said seats and provided at their outer exposed ends with nuts for adjustably securing the knives to their seats, adjusting screws threaded in said offset walls and bearing at their inner ends against the outer edges of the knives, said adjusting screws and the nuts on said bolts being accessible outside of the knife supporting section of the case, and a rotary cutter head mounted in said case and provided with knives arranged to coöperate with the other knives.

3. In a wood chipping machine the combination of a rotary cutter head having inwardly converging conical faces and provided with knives, a case in which said cutter head is mounted having a removable section formed with inwardly converging knife seats in planes approximately tangent to the conical faces of the cutter head and on its lower side another knife seat approximately

radial to the cutter head and perpendicular to its conical faces, and knives attached to said converging seats and a V-shaped knife attached to said radial seat and adapted to 5 coöperate with the knives of the cutter head to reduce to chips any splinters or fragments escaping the other stationary knives.

In witness whereof I hereunto affix my signature in presence of two witnesses.

GEORGE M. PELTON.
